(57) **CLAIM**

The ornamental design for a hair removal device, as shown and described.

DESCRIPTION

FIG. 1 is an exploded top, front, left side perspective view of a hair removal device;

FIG. 2 is an exploded bottom, rear, left side perspective view of a hair removal device;

FIG. 3 is an exploded front view of a hair removal device shown in FIG. 1;

FIG. 4 is an exploded rear view of a hair removal device shown in FIG. 1;

FIG. 5 is an exploded left side view of a hair removal device shown in FIG. 1;

FIG. 6 is an exploded right side view of a hair removal device shown in FIG. 1;

FIG. 7 is an exploded top view of a hair removal device;

FIG. 8 is an exploded bottom view of a hair removal device; and,

FIG. 9 is a combined state perspective view of a hair removal device.

The broken lines in the drawings depict portions of the hair removal device that form no part of the claimed design.
